D 11,479

Design No. 11,479, dated October 28, 1879

UNITED STATES PATENT OFFICE.

CHARLES E. HAVILAND, OF LIMOGES, FRANCE.

DESIGN FOR COVERED AND HOLLOW WARE.

Specification forming part of Design No. **11,479**, dated October 28, 1879; application filed October 3, 1879.
[Term of patent 3½ years.]

To all whom it may concern:

Be it known that I, CHARLES EDWARD HAVILAND, a citizen of the United States, now residing in Limoges, France, have invented a certain Design for Hollow, Flat, and Covered Ware, of which the following is a full, clear, and exact description and specification, reference being had to the photographic illustration accompanying it and forming part thereof, in which—

A is the braided handle shown looped into the surface of the ware. B are the curved corners of the dish or ware, joining the sides by reverse curves, the sides C are also curvi-

linear or waving, as shown, the whole upper edge forming what I will call a "waving" sided parallelogram.

What I claim as my invention, and desire to secure by Letters Patent, is—

The design for a dish of hollow, flat, or covered ware, shaped as shown and described, with the handle looped into the material, as shown.

CH. ED. HAVILAND.
